UNITED STATES PATENT OFFICE.

WILLIAM S. GIBSON, OF OSSINING, NEW YORK.

INVALID-REST FOR BEDS.

1,171,712.

Specification of Letters Patent.

Patented Feb. 15, 1916.

Application filed March 6, 1915. Serial No. 12,575.

To all whom it may concern:

Be it known that I, WILLIAM S. GIBSON, a citizen of the United States, residing at Ossining, in the county of Westchester and 5 State of New York, have invented new and useful Improvements in Invalid-Rests for Beds, of which the following is a specification.

This invention contemplates the provision 10 of an invalid rest especially designed for use in sick rooms in connection with a bed, and adapted to be arranged upon the latter for supporting the patient in upright position when desired.

15 The invention aims to provide a device of this character capable of being quickly folded in compact form to occupy a minimum amount of space when not in use.

20 A further object of the invention resides 20 in the provision of a device of this nature wherein the various parts can be readily set up in position for use and adjusted to the comfort of the patient.

25 Other objects will appear as the nature of the invention is better understood from the following description, wherein the structure is fully described in detail.

30 In the drawings forming a part of this application like numerals of reference indicate similar parts in the several views and 30 wherein:—

Figure 1 is a perspective view showing the device in position for use. Fig. 2 is a 35 plan view of the device folded. Fig. 3 is an enlarged detail view of one corner of the foot rest showing its connection with the base. Fig. 4 is an enlarged detail view of the forward ends of the arms showing the 40 connection of the table therewith. Fig. 5 is a view showing the connection between the back of the rest and the head board of the bed.

45 Referring more particularly to the drawing A indicates the base frame comprising the spaced parallel bars, each of which include telescopic sections 6 and 7 respectively, the sections 6 telescoping within the sections 7 and held in any desired position by means 50 of the set screw 8.

55 The back of the device which may be constructed from cane or any other suitable material is indicated at 9 and pivotally connected at its lower end with the sections 7 in any suitable manner as at 10. Rising from a point adjacent the forward ends of the sections 7 are spaced pairs of ears 11 be-

tween which are pivotally mounted the vertical members 12 of the arms of the device, which latter are pivotally connected to the forward ends of the horizontal members 13 60 of the arms. The members 13 are provided with a longitudinal series of apertures 14 adjacent the opposite ends thereof for interchangeable engagement with hook-like members 15 projecting laterally from the corner 65 posts of the back 9, whereby the arms may be adjusted longitudinally with respect to the base upon adjustment of the sections 6 and 7 of the base.

Supported by the forward ends of the 70 members 13 of the arms is a table 16, connected to one of the arms by means of a ball and socket connection 17, and detachably connected to the other arm by means of a hook and eye connection 18, to permit the 75 table to be swung to one side of and in parallelism with one of the arms in folded position as shown in Fig. 2. Depending from the underside of the table, and hingedly connected therewith are supporting 80 rods 19 adapted for interchangeable engagement with the vertical series of notches 20, formed in the vertical member 12 of the arms, whereby the table may be adjusted 85 vertically with respect to the base.

Arranged at the forward ends of the sections 6 of the base is a foot rest 21, being connected therewith by means of a ball and socket connection 22 at one corner and a hook and eye connection 23 at the opposite 90 corner thereof, to permit the foot rest to be detached at this point and swung upon its ball and socket connection to one side of and in parallelism with the section 6 to folded position. The foot rest 21 may be constructed from any suitable material, and arranged vertically in set up position, and by reason of the connection between the foot rest and the sections 6 of the base, the former may be adjusted vertically, and held 95 in any desired degree of inclination by means of the toothed bars 24 engaging the lower edge of the slots 25, through which the bars 24 project from the sections 6.

Secured to the back 9 are brace bars 26 105 comprising telescopic sections 27, the outermost section being formed with a bracket 28 adapted to be clamped upon the corner post of the bed by means of the set screws 29. The bracket of course can be designed 110 to accommodate the particular shape of object to which it is to be secured. By reason

of this construction the sections 27 of the brace bars may be adjusted and locked by means of the set screw 30 with a view of maintaining the back at any degree of inclination to the comfort of the patient.

Secured to the side rails of the bed are leather brace straps 31 having their opposite ends detachably connected to the horizontal members 13 of the arms of the device as shown.

As will be readily understood the device is primarily intended to be used at meal time, and when its use is desired the parts are arranged in set up position and placed upon the bed in the manner clearly shown in Fig. 1. Obviously the back 9 and foot rest 21 may be properly adjusted to the comfort of the patient, and the table 16 adjusted to bring the latter within convenient reach of the patient.

When it is desired to remove the chair from the bed, the brace straps 31 are detached from the arms 13, and the clamp 28 removed from the corner posts of the bed, subsequent to which the various parts may be readily and quickly folded in the manner shown in Fig. 2. In this operation the foot rest 21 is first detached from one of the sections 6 of the base frame, and swung upon its ball and socket connection to one side of the other of the sections 6 and in parallelism therewith. The sections 6 are then moved within the sections 7 of the base, after which the table 16 is unhooked from one of the arms 13 and swung upon its ball and socket connection 17 to one side of and in parallelism with the other arm 13, it of course being understood that the brace bars 19 are first disengaged from the notches 20. The members 13 of the arms are then unhooked from the back 9, permitting the latter to fold upon the base, and the arms to be subsequently folded upon the back, thus producing a compact structure which will occupy but small space, and which may be placed underneath the bed when not in use if so desired.

The various parts of the device may be constructed from any suitable material and of any desired dimensions.

It is believed that from the foregoing description the nature and advantages of the invention will be readily apparent without requiring a more extended explanation and therefore the same has been omitted. However I desire to have it understood that various changes in the construction and arrangement of parts may be resorted to when desired as fall within the scope of the appended claims.

What is claimed is:—

1. A device of the class described comprising a longitudinally adjustable base frame, a back pivotally secured to one end of the base, arms pivotally supported on the

base and adjustably connected with the back, a foot rest adjustably mounted on the opposite end of the base, and means for holding said foot rest in different adjusted inclined positions.

2. A device of the class described comprising a longitudinally adjustable base frame, a back pivotally secured to one end of the base and adapted to be folded thereupon, arms pivotally mounted on the base and pivotally connected with the back and adapted to be positioned upon said back when folded, a foot rest pivotally supported at the opposite end of the base, and adapted to be swung to one side and in parallelism therewith to folded position.

3. In a device of the class described, a base including adjustable sections, a back pivotally secured to one of said sections, arms carried by the said section adjustably connected with the back, a table supported by said arms, and a foot rest supported by the other of said sections.

4. In a device of the class described, a base including adjustable sections, a back pivotally mounted upon one of said sections, supports rising vertically from the said section and pivotally connected therewith, arms connecting the supports with said back, said arms having adjustable connection with the latter and movable longitudinally of said base, and a foot rest on the forward end of the other of said sections.

5. In a device of the class described, a base including adjustable sections, a back pivotally mounted at the end of one of said sections, supports rising from the opposite end of the section and pivotally connected thereto, a table detachably and swingingly mounted on said supports, adjustable connections between said back and supports, and a foot rest on the forward end of the other of said sections of the base.

6. In a device of the class described, a base, a back pivotally connected at one end of the base, arms mounted on the base and pivotally connected therewith, adjustable connections between said arms and said back, and a table carried by said arms, said table being adjustable with relation to the base independently of the said arms.

7. In a device of the class described, a base including adjustable sections, a back pivotally connected at one end to one of the said sections, arms pivotally mounted upon said section and detachably connected with said back, a table carried by said arms, said table being detachably connected with one of the arms, and pivotally connected with the other to permit the table to be swung to one side of the last mentioned arm in folded position, and a foot rest on the forward end of the other of said base sections.

8. An invalid rest adapted to be supported upon a bed, comprising a base in-

cluding adjustable sections, a back pivotally secured at the rear end of one of said sections, a foot rest at the forward end of the other of said sections, arms adjustably connected with said back, a table carried by said arms, and an adjustable connection between the said back and bed.

9. In a device of the class described comprising a base, a back pivotally connected at one end of the base and adapted to be folded upon said base, arms pivotally connected with said base and detachably secured to

the back and adapted to be positioned upon said back when folded, and a table, said table being pivotally secured to one of said arms and adapted to be swung to one side and in parallelism therewith in folded position.

In testimony whereof I affix my signature in presence of two witnesses:

WILLIAM S. GIBSON.
